Primary Examiner — Brett Miller

(57) **CLAIM**

The ornamental design for a barbecue apparatus, as shown and described.

DESCRIPTION

FIG. 1 is a perspective view of the barbecue apparatus showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a perspective view of the barbecue apparatus from another angle of view; and,

FIG. 9 is a perspective view of my new design portrayed in FIG. 8 in use.

The parts in broken lines of FIG. 1 to 9 are for illustrative purpose only and are not part of the claimed design.

1 Claim, 9 Drawing Sheets
